Primary Examiner — Paula Greene(74) *Attorney, Agent, or Firm* — McKee, Voorhees & Sease, P.L.C.(57) **CLAIM**

We claim the ornamental design for a vehicle outside door handle, substantially as shown and described.

DESCRIPTION

FIG. 1 is a perspective view of a vehicle outside door handle showing our new design;

FIG. 2 is an end view thereof;

FIG. 3 is an opposite end view thereof;

FIG. 4 is a side elevational view thereof;

FIG. 5 is an opposite side elevational view thereof; and,

FIG. 6 is a top plan view thereof.

The broken lines form no part of the claimed design.
